UNITED STATES PATENT OFFICE.

OTTO KAMPFE, OF NEW YORK, N. Y.

BOTTLE-CLOSURE.

1,131,708.

Specification of Letters Patent. Patented Mar. 16, 1915.

Application filed February 5, 1914. Serial No. 816,708.

To all whom it may concern:

Be it known that I, OTTO KAMPFE, a citizen of the United States of America, residing at New York city, borough of Brooklyn, county of Kings, and State of New York, have invented certain new and useful Improvements in Bottle-Closures, of which the following is a full, clear, and exact description.

10 This invention relates to improvements in closures more particularly adapted for milk-bottles such as are commonly used by dairy-men to deliver milk for family purposes.

15 The object of this invention is to provide an inexpensive sanitary closure or stopper that can be easily and quickly applied to a milk bottle, the closure acting to keep the contents of the bottle free from dirt, flies or contact with the air.

20 While my improved closure will accomplish the above results, it will not, in the least, interfere with the pouring of the milk from the bottle, as the closure will fall away from the mouth of the bottle when the bottle 25 is tipped for the purpose of pouring milk therefrom.

The device can be easily inserted into the mouth of the bottle by simply compressing the clamping or locking element or anchor 30 for the cap, and it can be easily removed by a strong pull. Other features of improvement will hereinafter appear.

I will now proceed to describe my invention in detail, the novel features of which I 35 will point out in the appended claims, reference being had to the accompanying drawing, forming part hereof, wherein:—

Figure 1 is a sectional view of the upper end of a milk bottle having my improved closure applied thereto; Fig. 2 is a sectional top plan view thereof on a reduced scale, the section being taken on a line 2—2 in Fig. 1; Fig. 3 is a diagrammatic view illustrating the device in position for pouring fluid 45 therefrom; and Fig. 4 is a view similar to Fig. 1 illustrating a modified form of closure.

As herein shown my improved bottle closure is illustrated as applied to a milk bottle 50 and consists of a plate or cap 1 formed to lie flat or in close contact with the upper edge of the bottle and over the mouth 2 thereof. As is usual in this class of bottle, the said bottle 3 is provided with a counter-bore 3^a 55 within which the paper or celluloid plugs or disks now usually employed, are forced.

My improved closure is designed to take the place of these paper plugs or disks.

To maintain the plate or cap 1 in proper relationship, at all times, with the open end 60 of the bottle I employ a clamp or anchor 4 provided with a spindle 5 which passes through an opening 5^a in the plate 1, the spindle 5 being provided with a ring or stop 6 at the outer end thereof. In this instance, 65 the clamp or anchor 4 consists of a resilient coil of wire, preferably German silver or other non-corroding material. For sanitary reasons the plate 1 is preferably made of German-silver, aluminum or some material 70 that will not rust or corrode, the design of the plate being optional.

The coiled anchor or clamp 4 will normally be larger in diameter than the counterbore 3^a; hence to insert it into the counterbore 3^a 75 it will be necessary to slightly compress it. After the anchor has been inserted into the counter-bore, it will be released and allowed to expand, thereby pressing firmly against the side wall of the counterbore and thus 80 anchoring it therein. To remove the anchor, a strong pull will be necessary; consequently, it will not fall out by gravity when the bottle is tipped.

As long as the bottle remains in a vertical 85 position, or even at an angle, provided the angle is not sufficient to cause the cap to break contact with the bottle, the mouth of the bottle will be covered; hence the contents will be kept free from contact with the air 90 or dirt.

To cause the contents of the bottle to flow therefrom, it is but necessary to tip the bottle, as shown in Fig. 3, at which time the plate 1 will fall away therefrom, providing 95 a passage through which the contents of the bottle will flow. The stop 6 will prevent the cap from falling off the spindle or guide 5. When the bottle is again tipped back to its normal position, the cap or plate 1 will fall 100 into place, as shown in Fig. 1.

In the form of device illustrated in Fig. 4, I provide a lock 7 for the plate 1, the same consisting of a ball or block of rubber, leather or the like or any substance having 105 a natural tendency to hug or grip the spindle 5, the block or ball being slidably mounted on the spindle as shown. When the lock 7 is pressed down upon the plate, as shown in Fig. 4, the bottle can be tipped or can 110 fall over, without spilling the contents thereof, as the said lock will firmly hold

the cap against the bottle; but when the cap is to be released, the block 7 can readily be moved to the dotted line position (Fig. 4).

Having now described my invention, what I claim and desire to secure by Letters Patent is:

1. A bottle closure consisting of a resilient clamp adapted for insertion into the mouth of a bottle, a centrally located stationary guide projecting vertically therefrom, a cover plate movable on said guide and provided with a central opening adapted for the free passage therethrough of said guide, and a stop at the outer end of said guide.
- 15 2. A bottle closure consisting of a coiled clamp of resilient material, a rigid guide extending therefrom, and a cover-plate slidably mounted on said guide, and adapted to move by gravity longitudinally thereof.

Copies of this patent may be obtained for five cents each, by addressing the "Commissioner of Patents, Washington, D. C."

3. A bottle closure consisting of a coiled 20 clamp of resilient material, a rigid guide extending therefrom, a cover plate slidably mounted thereupon, and a lock for said plate carried by said guide.

4. A bottle -closure comprising a clamp 25 adapted for insertion into the mouth of a bottle, a stationary post projecting from said clamp, and a cover -plate slidably mounted on said post and adapted to tilt, when free from contact with the bottle, in 30 a direction corresponding with any tilting of the bottle.

Signed at New York city, N. Y., this 4 day of February, 1914.

OTTO KAMPFE.
